UNITED STATES PATENT OFFICE.

J. CORWIN CRUM, OF SCOTT CITY, KANSAS.

RAIL-FASTENER.

1,224,078.

Specification of Letters Patent. Patented Apr. 24, 1917.

Application filed January 29, 1917. Serial No. 145,235.

To all whom it may concern:

Be it known that I, J. CORWIN CRUM, a citizen of the United States, residing at Scott City, in the county of Scott and State of Kansas, have invented a new and useful Rail-Fastener, of which the following is a specification.

The device forming the subject matter of this application is adapted to be employed for holding a rail to a tie, and one object of the invention is so to improve the construction of the tie that the same will cooperate with a movable retainer in holding the rail.

Another object of the invention is to improve the construction of the retainer, both as to its form, and as to the means whereby the retainer is mounted on the tie adjustably.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed; it being understood that changes in the precise embodiment of the invention herein disclosed can be made within the scope of what is claimed, without departing from the spirit of the invention.

In the accompanying drawing:

Fig. 1 shows in longitudinal section, a portion of a tie constituting a part of the present invention;

Fig. 2 is a longitudinal section of the tie, the rail and other parts being shown in place;

Fig. 3 is a top plan of the structure shown in Fig. 2;

Fig. 4 is a cross section taken approximately on the line 4—4 of Fig. 2;

Fig. 5 is a perspective view showing a slight modification in the rail; and

Fig. 6 is a fragmental longitudinal section showing a modification in the retainer.

In carrying out the present invention there is provided a trough-shaped metal tie 1 including a base 2 and upstanding sides 3. In the base 2, a depressed, transverse seat 4 is formed. The sides 3 of the tie 1 are provided with notches 5, each side 3 having a recess 6 prolonged longitudinally of the tie and communicating with the notch

5, the recess 6 lying above a portion of the seat 4. Adjacent the recess 6, the notch 5 is defined by a vertical edge 7, the opposite edge of the notch being inclined as shown at 8, and terminating at its lower end adjacent one end of the depressed seat 4 in the base 2. In the sides 3 of the tie close to the base 2 and adjacent the inclined edge 8 of the notch 5, guide ways 9 are fashioned. The base 2 may be provided with a threaded opening 10.

The numeral 11 denotes a rail including a ball 12, a web 14 and a flange 15. In practical operation, the flange 15 of the rail is lodged in the seat 4, one side portion of the flange 15 being received in the recess 6, and one side of the web 14 abutting against the vertical edges 7 of the notches 5 in the sides 3 of the tie 1. Owing to inclination of the edges 8 of the notches 5, the rail 11 may be mounted in place readily, as shown in Fig. 2. The web 14 of the rail 11 has a projection 16, which, abutting at its ends against the sides 3 of the tie 1, prevents the rail from moving endwise.

The numeral 17 denotes, generally, a retainer including a body 18 mounted to slide on top of the base 2 of the tie, the edges of the body 18 being slidably received in the guideways 9, so that the retainer can be advanced and retracted with respect to the rail 11. The body 18 of the retainer merges into a reduced extension 19 having an upstanding lip 19. The extension 19 is adapted to rest on top of the flange 15 of the rail when the retainer is advanced, and the lip 19 abuts against one side of the web 14 as clearly shown in Fig. 2. Since the extension 19 is of less width than the body 18 of the retainer, the retainer can be retracted in the guideways 9. The body 18 of the retainer 17 has a longitudinal slot 20 through which passes a headed set screw 21, threaded into the opening 10 in the base 2 of the tie 1.

After the rail has been mounted in place as shown in Fig. 2, the container 17 may be advanced until it assumes the position outlined in Fig. 2, whereupon the screw 21 may be tightened down by a wrench or key, the head of the screw engaging the base or body 18 of the retainer, to prevent the retainer from moving rearwardly.

In case that the invention is used with an old rail 22, as shown in Fig. 5, a projection 23, corresponding to the projection 16, may

be attached to the web of the rail by securing elements 24, the projection 16 being formed integrally with the web 14 of the rail 11.

In the modified form shown in Fig. 6, the base of the tie appears at 25 and the sides are shown at 26, the same having guide-ways 27 receiving a retainer 28 carrying a set screw 29. In this form of the invention, the set screw 29 is threaded into the retainer 28, the retainer being devoid of the slot 20 of Fig. 3, and there being no hole 10 in the base, to receive the set screw.

Having thus described the invention, what is claimed is:

15 In a device of the class described, a trough-shaped tie including a base and sides, the sides having notches including exten-

sions prolonged longitudinally of the tie into the sides; a rail located in the notches and resting on the base, the rail including a 20 web and a flange, one portion of the flange being received in the extensions, and the web having a projection engaged between the sides of the tie; and a removable retainer carried by the base and overhanging the opposite portion of the flange of the rail. 25

In testimony that I claim the foregoing as my own, I have hereto affixed my signature in the presence of two witnesses.

J. CORWIN CRUM.
